(57) **CLAIM**

The ornamental design for a perambulator, as shown and described.

DESCRIPTION

FIG. 1 is a front view of a perambulator showing my new design;

FIG. 2 is a front perspective view thereof;

FIG. 3 is a rear perspective view thereof;

FIG. 4 is a another rear perspective view thereof; and,

FIG. 5 is a left side view thereof, the right side being a mirror image.

The crosshatching shown in the above Figures is understood to represent a mesh material.
